UNITED STATES PATENT OFFICE.

JOHN F. O'CONNOR, OF CHICAGO, ILLINOIS, ASSIGNOR TO WILLIAM H. MINER, OF CHAZY, NEW YORK.

SIDE BEARING FOR RAILWAY-CARS.

1,248,535.

Specification of Letters Patent. Patented Dec. 4, 1917.

Application filed April 9, 1917. Serial No. 160,648.

To all whom it may concern:

Be it known that I, JOHN F. O'CONNOR, a citizen of the United States, residing at Chicago, in the county of Cook and State of Illinois, have invented a certain new and useful Improvement in Side Bearings for Railway-Cars, of which the following is a full, clear, concise, and exact description, reference being had to the accompanying drawings, forming a part of this specification.

My invention relates to improvements in side bearings for railway cars.

The object of my invention is to provide a simple and efficient side bearing.

In the drawings forming a part of this specification, Figure 1 is a vertical longitudinal section of a side bearing embodying my invention. Fig. 2 is a cross section thereof.

In the drawings, the numeral 10 indicates a side bearing appropriately secured to a bolster, as, for instance, an upper or body bolster 11. The opposed bolster, as, for instance, the truck bolster, is indicated by the numeral 12. The bearing comprises a base member 13 suitably secured to a bolster by the ears 14 and the rivets 15. The said casing is a hollow five-sided member having a stud or tongue 16 interiorly extended from the plate 17 thereof, and preferably integral therewith. The said member 16 has a rounded end 18 which engages against the internal face 19 of the segmental roller 20. For convenience, we designate the said roller as a semilunar roller, and the face 19 the inner faces thereof. The outer face 21 is adapted to bear against the bearing plate 22 upon the opposed bolster, as, for instance, the lower or truck bolster 12 to which it is secured.

It will be observed that upon longitudinal movement of one bolster end in reference to the other, as, for instance, movement to the lefthand of the upper bolster, as illustrated in Fig. 1 of the drawing, the semilunar anti-friction roller will roll upon the bearing plate 22 and about the end of the tongue 16 as a center until the inner face of the roller strikes the side 23 of the tongue, when the relative position of the

parts will be as illustrated by the dotted lines in Fig. 1 of the drawings. Upon the contrary longitudinal movement of the bolsters the converse action will occur. The displacement of the roller from the base member is prevented by the ends 25—25 thereof, the sides 26—26 thereof, and the engagement of the same upon the bearing plate 21.

I claim:

1. In a side bearing for railway cars, a hollow base member adapted to be mounted upon a bolster, a bearing plate upon an opposed bolster, a semilunar roller mounted in the base member, the base member being provided with a tongue adapted to engage the inner face of the semilunar roller.

2. In a side bearing for railway cars, in combination: a bolster; a hollow base member secured thereto; an opposed bolster, and a semilunar roller; the base member being provided with a stud engaging the inner face of the roller, the roller being adapted to roll upon the opposed bolster from a center formed by the end of the said stud.

3. In a side bearing for railway cars, a bolster, a hollow base member secured thereto, an opposed bolster, a roller mounted in the base member, the base member being provided with a stud engaging the said roller and about a portion of which as a center the roller is adapted to revolve.

4. In a side bearing for railway cars, a bolster, a base member secured thereto, an opposed bolster, a semilunar roller mounted in the base member, the base member being provided with a tongue engaging the inner face of the semilunar roller and forming a center for the roller to revolve upon.

5. In a side bearing for railway cars, a base member, a semilunar roller mounted therein, an opposed bearing plate engaged by said roller, a base member having a stud radially arranged in reference to the roller and forming a member about which the roller may revolve.

In witness that I claim the foregoing I have hereunto subscribed my name this 20th day of Mar., 1917.

JOHN F. O'CONNOR.
